DISPLAY DEVICE

Julius Horwath, Chicago, Ill., assignor to Badger
Carton Company, Milwaukee, Wis., a corpo-
ration of Wisconsin

Application April 1, 1935, Serial No. 14,077

5 Claims. (Cl. 40—126)

This invention relates to improvements in display devices, and more particularly to a device for display and advertising purposes especially intended to be disposed on counters, show cases, window cabinets, and similar places.

There are on the market various collapsible display devices of the type wherein a frame with an inset panel for advertising material, is supported by an integral easel. In all of such prior devices a large number of separate easel, frame and stand parts are required, necessitating numerous die-cutting and assembling operations to produce a complete device.

It is, therefore, an object of the present invention to provide a collapsible display device of the above referred to type formed of a minimum number of parts whereby manufacture thereof is rendered simple and relatively inexpensive.

A further object of the invention is to provide a framed display device wherein the frame panel is adapted to be disposed in a plane rearwardly of the plane of the frame sides, but is integral with and folded out of the stock of the side members of the frame.

A further object of the invention is to provide a framed display device of the character described which can be easily manipulated from collapsed to set-up position by a dealer and which is held in set up condition by locking strips integral with top and bottom portions of the frame.

Another object of the invention is to provide a three-piece advertising display frame and stand having parts thereof in different planes, including a stand portion, a frame portion, and an upper wing portion.

Prior devices of the general type under consideration could not be collapsed into perfectly flat form and hence required considerable storage space, and in the shipment thereof special built up protecting containers were required.

An additional object of the present invention is to provide a display device which overcomes these difficulties and which can be collapsed into a perfectly flat condition, facilitating storing, packing and shipping of numbers of the same.

A further object of the invention is to provide a collapsible, framed display device which is of very simple construction, which is easy to manipulate, which is attractive in appearance, which is strong and durable, and which is well adapted for the purposes set forth.

With the above and other objects in view the invention consists of the improved display de-

vice, and its parts and combinations as set forth in the claims, and all equivalents thereof.

In the accompanying drawings in which the same reference characters indicate the same parts in all of the views:

Fig. 1 is a view of the main blank of the device which provides the frame sides and inset panel;

Fig. 2 is a view of the lower blank which provides the lower frame member, the display stand and one of the locking members for the device;

Fig. 3 is a view of the upper blank which provides the upper frame member and the other locking member;

Fig. 4 is a plan view of the assembled members of Figs. 1, 2 and 3 providing the display device and in collapsed condition;

Fig. 5 is a sectional view thereof taken on line 5—5 of Fig. 4 with a broken line showing of the folded out position of the panel and associated parts;

Fig. 6 is a longitudinal sectional view taken on line 6—6 of Fig. 4;

Fig. 7 is a front view of the device in folded out or set-up condition;

Fig. 8 is a transverse sectional view taken on line 8—8 of Fig. 7;

Fig. 9 is a vertical section through a perspective of the device; and

Fig. 10 is an enlarged detail sectional view taken on line 10—10 of Fig. 7.

Referring now more particularly to the drawings it will appear that the main blank, designated by the numeral 12, includes a central panel 13, a lower inset portion 14, frame sides 15 and 16, and a top wing 17. Between portions of the wing 17 and top extensions of the frame sides 15 and 16 are connecting strips 18 connected to their respective members along lines of fold 19 and 20. There are slits 21 between the upper portions of the panel 13 and the top extensions of the frame sides 15 and 16. The lower outer edge portions of the wing 17 are also separated from the frame side extensions, as along 45 the lines 22. Foldably connected to the frame sides 15 and 16 by fold lines 23, and to the sides of the panel 13 by fold lines 24, are longitudinal panel strips 25. Lower extensions of the frame sides 15 and 16 are connected to the portion 14 by strips 26 which are foldably connected to the portions they connect. Lines of cut 27 separate lower edge portions of the panel 13 from the lower extensions of the frame sides.

A blank to form the display stand, the lower

frame portion, and lower lock is depicted in Fig. 2 and is indicated generally by the numeral 28. This blank includes a lower frame portion 29 having a pair of foldably connected locking strips 5 30 and 31 foldably connected to its outer edge, as at 32. The remainder of said blank includes sections separated from portions of adjacent sections by lines of cut and fold lines to provide, in the assembled device when the parts are 10 opened up, various stepped display shelves 33, 34 and 35 respectively. Also included in said blank 28 is a section 36 adapted to be secured against the lower front face portion of the blank 12 and being foldably connected to another section 37 15 which ultimately forms the bottom of the display stand and which is foldably connected with the remainder of said blank.

The blank for the top of the frame is designated 38 and includes a quadrilateral frame section 39 and a pair of foldably connected, narrow locking strips 40 and 41 foldably associated therewith. The free edge of the strip 40 is provided with notches 42, for locking purposes, and likewise the free edge of the lower locking strip 25 30 has notches 43 for the same purpose.

The blanks 12, 28 and 38, shown in detail in Figs. 1, 2 and 3, are mounted with respect to one another in the manner shown in Figs. 4, 5 and 6. The portion 39 of the blank 38 is glued 30 to the upper extensions of the frame sides 15 and 16, and below the wing 17. The portion 39 is unsecured with respect to the adjacent portion of the panel 13 and the connecting strips 18. The locking strips 40 and 41 extend outstretched over 35 the upper face portion of the panel.

With respect to the lower blank 28, the portion 36 thereof is glued to the lower portions of the frame side extensions 15 and 16 and its lower edge is coincident with the lower edge of 40 the blank 12. The display stand bottom section 37 is folded out flatly as a continuation of the portion 36, and the other portions of the blank 28 are folded over onto the sections 33 and 35 and the lower portion of the blank 12. The 45 section 29, save for the steps 33, 34 and 35 separated therefrom by lines of cut, is secured to the lower face portion of the blank 12, with the locking strips 30 and 31 extending outstretched over the lower portion of the panel 13. A folding easel 44 is secured to the rear of the panel and is adapted to be folded flatly thereagainst. It will thus appear that in its assembled and collapsed form, the display device is very flat and compact and occupies a minimum amount 55 of storage space. Also, due to the flat arrangement, the devices may be readily packed in ordinary containers for shipment.

When a user desires to set up the device for advertising and display purposes the first step is 60 to unfold the inset panel 13. This is accomplished by swinging it away from the plane of the blank 12 on the various strips 18, 24, 25 and 26 to the position of Figs. 7 and 9. The panel is readily locked in this unfolded position by 65 folding each set of locking strips 30, 31 and 40, 41 inwardly and tucking the strips 30 and 40 inwardly against lower and upper face portions of the panel. Said strips in this position, cooperate with the side strips 25 to surround the exposed 70 portion of the panel. The notches 42 of the upper locking strip engage portions of the members 18 (see Fig. 10) while the notches 43 of the lower locking strip engage upper edge portions of the members 26. The stepped portions of the 75 display stand may next be unfolded and the portion

37 is folded at right angles to the attached section 36 to form the display stand bottom, with the steps 33, 34 and 35 assuming the positions shown in Figs. 7, 8 and 9.

To support the display device on a counter, 5 window ledge, or the like, in a position slightly inclined from vertical, the easel 44 is turned outwardly, as in Fig. 9, and is locked in supporting position by a notched tab 45. The wing 17 and the panel 13 may bear suitable advertising material and decorations, while articles to be displayed may be supported on the various steps.

From the foregoing description it will be seen that the improved display stand employs a minimum number of readily connectable parts. Die 15 cutting and assembly is simplified and in addition, a user may set up a device with a minimum of effort and time. Due to the fact that the device may be collapsed very flatly it is easy to store and ship. The display device is, further- 20 more, of simple, attractive and unique construction, and is well adapted for the purposes described.

What is claimed as the invention is:

1. A display device, comprising a sheet of material 25 having a central panel portion foldably connected to side portions thereof, said panel portion being foldable from a position against the sheet to a plane parallel therewith and offset therefrom, and permanently attached foldable 30 means engageable directly with opposite end portions of the panel to releasably hold it in said latter position.

2. A display device, comprising a sheet of material 35 formed with side frame portions and an integral central panel foldably connected with said side frame portions and foldable from a position thereadjacent to an offset parallel position, end frame members permanently secured transversely to pairs of ends of the side frame 40 portions and permitting folding movements of said panel, and locking means integral with intermediate portions of said end frame members and releasably engageable directly with the panel to hold it in offset position.

3. A display device, comprising a sheet of material 45 formed with side frame portions and an integral central panel foldably connected with said side frame portions and foldable from a position thereadjacent to an offset parallel position, end frame members secured transversely 50 to pairs of ends of the side frame portions, a display stand integral with and foldable from one of said end frame members to form stepped supporting shelves, and locking means integral 55 with said end frame members and releasably engageable with the panel to hold it in offset position.

4. A display device, comprising a sheet of material 60 formed with side frame portions and an integral central panel foldably connected along its side edges with said side frame portions, said panel being movable from a flat position against the sheet to a rearwardly offset, parallel position, 65 a wing integral with an end edge of said panel and separated from the side frame portions so as to move with the panel, end frame members secured transversely to pairs of ends of the side frame portions, a display stand integral with 70 and foldable from one of said end frame members to form stepped supporting shelves, locking means integral with said end frame members and releasably engageable with the panel to hold it 75 in offset position, and an easel foldably carried

by a rear portion of the device to support it in upright position.

5. In a collapsible display device, a single sheet forming a central panel and side frame members, side strips interposed between side edges of the panels and side frame members and foldably connected with all of the same, a permanently attached single sheet forming a lower frame member and having integral locking strips

foldably connected along one edge thereof, and another permanently attached single sheet forming an upper frame member and having integral locking strips foldably connected along one edge thereof, all of said locking strips being foldable angularly inwardly to directly engage portions of the panel to releasably hold it in an inwardly offset position relative to the frame members. 5

JULIUS HORWATH.
